UNITED STATES PATENT OFFICE

171,600

NUT CRACKER

Waldemar Johnson, Chicago, Ill.

Application October 19, 1953, Serial No. 27,224

Term of patent 14 years

(Cl. D44—1)

To all whom it may concern:

Be it known that I, Waldemar Johnson, a citizen of the United States, residing at Chicago, in the county of Cook and State of Illinois, have invented a new, original, and ornamental Design for Nut Cracker, of which the following is a specification, reference being had to the accompanying drawing forming a part hereof.

Fig. 1 is a side elevational view of a nut cracker showing my new design;

Fig. 2 is a top plan view thereof; and

Fig. 3 is an end elevational view thereof.

I claim:

The ornamental design for a nut cracker, as shown.

WALDEMAR JOHNSON.
